(57) **CLAIM**

The ornamental design for a stacked arrangement of water-soluble cleaning strips and child-resistant container, as shown and described.

DESCRIPTION

FIG. 1 is a top-front exploded perspective view of a stacked arrangement of water-soluble cleaning strips and child-resistant container, showing my new design;

FIG. 2 is a top-rear exploded perspective view thereof;
FIG. 3 is a top-front perspective view thereof, the child-resistant container of the design omitted for clarity of illustration;

FIG. 4 is a left-side elevational view of FIG. 3, the right-side elevational view being a mirror image thereof;

FIG. 5 is a top plan view of FIG. 3, the bottom plan view being a mirror image thereof;

FIG. 6 is a front elevational view of FIG. 3, the rear elevational view being a mirror image thereof;

FIG. 7 is a top-front exploded perspective view thereof, the stacked arrangement of water-soluble cleaning strips of the design omitted for clarity of illustration;

FIG. 8 is a bottom-front exploded perspective view of FIG. 7;

FIG. 9 is a left-side elevational view of FIG. 7, the right-side elevational view being a mirror image thereof;

FIG. 10 is a top plan view of FIG. 7;

FIG. 11 is a bottom plan view of FIG. 7;

FIG. 12 is a top-front perspective view thereof, with the stacked arrangement of water-soluble cleaning strips of the design disposed inside of the child-resistant container of the design;

FIG. 13 is a bottom-front perspective view of FIG. 12;

FIG. 14 is a left-side elevational view of FIG. 12, the right-side elevational view being a mirror image thereof;

FIG. 15 is a top plan view of FIG. 12;

FIG. 16 is a bottom plan view of FIG. 12;

FIG. 17 is a front elevational view of FIG. 12;

(Continued)

FIG. 18 is a rear elevational view of FIG. 12;
 FIG. 19 is a top-front exploded perspective view of an alternate embodiment of a stacked arrangement of water-soluble cleaning strips and child-resistant container;
 FIG. 20 is a top-rear exploded perspective view thereof;
 FIG. 21 is a top-front perspective view thereof, one of the two adjacent stacks of water-soluble cleaning strips of the stacked arrangement of water-soluble cleaning strips of the design omitted for clarity of illustration, the child-resistant container of the design also omitted for clarity of illustration;
 FIG. 22 is a left-side elevational view of FIG. 21, the right-side elevational view being a mirror image thereof;
 FIG. 23 is a top plan view of FIG. 21, the bottom plan view being a mirror image thereof;
 FIG. 24 is a front elevational view of FIG. 21, the rear elevational view being a mirror image thereof;
 FIG. 25 is a top-front exploded perspective view thereof, the stacked arrangement of water-soluble cleaning strips of the design omitted for clarity of illustration;
 FIG. 26 is a bottom-front exploded perspective view of FIG. 25;
 FIG. 27 is a left-side elevational view of FIG. 25, the right-side elevational view being a mirror image thereof;
 FIG. 28 is a top plan view of FIG. 25;
 FIG. 29 is a bottom plan view of FIG. 25;
 FIG. 30 is a top-front perspective view thereof, with the stacked arrangement of water-soluble cleaning strips of the design disposed inside of the child-resistant container of the design;
 FIG. 31 is a bottom-front perspective view of FIG. 30;
 FIG. 32 is a left-side elevational view of FIG. 30, the right-side elevational view being a mirror image thereof;
 FIG. 33 is a top plan view of FIG. 30;
 FIG. 34 is a bottom plan view of FIG. 30;
 FIG. 35 is a front elevational view of FIG. 30; and,
 FIG. 36 is a rear elevational view of FIG. 30.
 The surface shading illustrated in the drawings is provided merely to highlight the contour of the design; it is not intended to be illustrative of texture or gloss. The evenly-broken lines in the drawings illustrate portions of the child-resistant container that form no part of the claimed design. The additional evenly-broken lines in FIGS. 19 and 20 illustrate one of the two adjacent stacks of water-soluble cleaning strips of the stacked arrangement of water-soluble cleaning strips that forms no part of the claimed design.
